UNITED STATES PATENT OFFICE.

THOMAS DOUGLAS JONES AND JOHN H. BARR, OF KANSAS CITY, MISSOURI; MARY BARR EXECUTRIX OF SAID JOHN H. BARR, DECEASED.

PHONOGRAPH RECORD.

1,425,486.

Specification of Letters Patent. Patented Aug. 8, 1922.

Application filed February 7, 1921. Serial No. 443,002.

To all whom it may concern:

Be it known that we, THOMAS DOUGLAS JONES and JOHN H. BARR, citizens of the United States, and residents of Kansas City, county of Jackson, State of Missouri, have invented a certain new and useful Improvement in Phonograph Records, of which the following is a complete specification.

This invention relates to phonograph disk records and has for its object to produce a record provided within the space surrounded by the sound reproducing grooves, with a score or groove to receive the needle after the sound reproduction has been accomplished, and guide the needle inward and then outward with respect to the axis of the record, and thereby eventually reverse the travel imparted to the tone arm by the engagement of the needle with the sound reproducing grooves of the record, this reverse or outward travel of the tone arm being utilized to effect the operation of the brake mechanism to arrest the rotation of the record. The mechanism in contemplation for actuation by the outward movement of the tone arm, will form the subject matter of another application for patent, and hence is not illustrated or described herein.

With this object in view, the invention consists in the provision in the face of the record, of a scoring or groove intersecting at its outermost point, one of the non-reproducing grooves or the innermost extremity of the final sound reproducing groove of the record, and extending first inward and then outward toward but not beyond the said non-reproducing or innermost extremity of the final sound-reproducing groove, as hereinafter described and claimed; and in order that it may be understood reference is to be had to the accompanying drawing, in which:—

Figure 1, is a face view of a phonograph record embodying the preferred form of the invention.

Figure 2, is a similar but fragmental view of a record of modified construction.

Referring now to the drawing in detail, the record 1 of the usual type and operation, is provided in Figure 1, with a circular scoring or groove 2 disposed eccentrically to the axis 3 of the record and at its point most remote from such axis, intersecting one of the usual non-reproducing grooves 4

surrounded by the sound re-producing 55 grooves 5 of the disk.

With this construction the said eccentric scoring or groove may intersect the inner extremity of the spiral reproducing groove if the record lacks the customary additional 60 inner grooves for guiding the needle without an attendant sound reproduction.

In Figure 2, the scoring 6, intersects either of the grooves mentioned as conventional in disk records, and curves inward from the 65 point of intersection to avoid a too sudden or abrupt inward jump or acceleration of the inward movement of the needle and tone arm, the scoring then extending as a chord or partial chord 7 of the innermost of the 70 customary grooves, so that it shall at first continue the inward travel of the needle and then reverse such travel, accomplishing the result in the same manner as the eccentric 75 groove 2 but more rapidly, as it effects the reverse or outward movement of the tone arm in less than a half revolution of the record as contrasted with the eccentric circular groove which starts the outward 80 swing of the tone arm at the end of a half revolution of the record. With the "chord" type of groove it is preferred that it shall intersect the innermost sound-reproducing 85 groove or one of the non-reproducing grooves at both ends, though it may intersect 90 at one end only, this being immaterial provided the brake actuating mechanism of the phonograph functions properly. It is also desirable that the scoring of either type or of any modification thereof, shall be slightly 95 deeper than the sound-reproducing and non-reproducing grooves, to insure the necessary reverse travel or swing of the tone arm. The same principle of construction can be applied in connection with the cylinder type 95 of record.

From the above description it will be apparent we have produced a phonograph record capable of imparting outward or reverse movement to the tone arm, and it is 100 susceptible of modification in minor particulars without departing from the principle of construction involved.

We claim:

1. A phonograph disk record provided on 105 its face within the space surrounded by the sound reproducing grooves, with a scoring or groove for receiving the needle of the

tone arm after the needle has completed its inward travel in said grooves, to cause said needle to move inwardly and then outwardly and impart corresponding movements to the tone arm.

2. A phonograph disk record provided within the space surrounded by the sound reproducing grooves, with a circular scoring

or groove disposed eccentrically of the axis of the record and at its point most remote 10 from said axis, intersecting the normal path of travel of the needle to cause the same and the tone arm to move inwardly within the space and then outwardly.

TOM DOUGLAS JONES.
JOHN H. BARR.
